POCKETBOOK COMPACT

Application filed March 11, 1930. Serial No. 434,905.

This invention relates to a pocket book compact, and has for an object to provide a compact which may simulate a pocket book in appearance and which will contain the 5 most important articles for a woman's toilet in handy and quickly accessible positions.

A further object of this invention is to provide a compact which will include a money purse and a mirror in such positions that 10 the mirror and the purse may be used without the necessity of exposing any of the other toilet or vanity articles and to provide means whereby each vanity article may be kept in a separate place where it can not get misplaced 15 or lost, whereby each article may have a separate compartment provided therefor, so that any article may be used without the necessity of disturbing the other articles.

With the foregoing and other objects in 20 view, this invention comprises the following constructions, combinations and arrangements of parts hereinafter set forth, disclosed and claimed as considered in connection with the accompanying drawing. In these drawings

Fig. 1 is a plan front view of one embodiment of this invention, showing the compact with one flap opened.

Fig. 2 is a similar view showing all the flaps 30 closed, and

Fig. 3 is a section on line 3—3 of Fig. 1.

This invention comprises a compact made up in simulation of a pocket book and consists broadly of a case or a panel and side 35 walls having flaps hinged to each side and having a plurality of the flaps fastenable at the center of the case or panel and having one flap overlapping the fastening means of the other flaps, thereby providing a closure 40 means, and further providing a handle or carrying strap on the back of the case or panel. There is shown at 10 a panel having side walls 11 and 12 and a bottom wall 13 and top wall 14, the panel and walls thus forming 45 a box-like receptacle or case. Secured across the outer or back side of the case or panel 10 is a holder or carrying strap 15 whereby the complete article may be easily carried by the user.

50 Hinged to each wall, and preferably al-

though not necessarily integral therewith is a flap which is to constitute a part of the closure for the compact. The flaps 16 and 17 on each of side walls 11 and 12 are each substantially triangular and their apexes meet 55 at approximately the center of panel 10. At the apex of each flap 16 and 17 is secured one element 18 of a snap fastener, while the other elements 19 of the snap fasteners are secured on a block 20 of wood or other suitable material which is glued to or otherwise firmly secured to the inside of panel 10 at the center thereof, whereby the flaps 16 and 17 may be folded to form part of the closure 60 means for the compact. Similarly hinged to 65 the bottom wall 13 is a substantially triangular flap 21 likewise having a fastener element 18 at its apex which may be secured to its mating element 19 in block 20. Hinged to wall 14 as at 22 is still another flap 23 which 70 is likewise substantially triangular, although its edges 24 and 25 may be curved as shown for decorative effect. Although opposite flaps 16 and 17 are substantially equal in size, flap 23 is substantially larger than its opposite 75 flap 21, and hence its apex overlaps the apexes of the flaps 16, 17 and 21. Secured in the apex of flap 23 is one element 26 of a fastening means, and its mating element 27 is secured on the outer side of its opposing 80 flap 23. As will be apparent, hinge 22 of flap 23 is set below the plane of the other hinges of the flaps 16, 17 and 21, and hence there is easier access to the interior of the compact when flap 23 is opened. Each of flaps 16, 17 85 and 21 serve to substantially divide the space in the case into separate compartments, while the space not covered by these flaps defines another compartment.

In operation, a vanity article is to be placed 90 in each of the compartments in the case, and another article may be placed on the inner side of the overlapping flap 23. Thus, the compartment beneath flap 21 may contain a lip stick case and container 28 while the compartments beneath flaps 16 and 17 may contain rouge and powder cases 29 and 30. These cases may be of any of the standard constructions carrying the powder either in the form 95 of a compact or as loose powder, and also 100

carry the usual powder puff for applying the powder. Thus, by opening anyone of flaps 16, 17 or 21, any one of the articles 29, 30 or 28 may be made available without disturbing 5 the other of these flaps or articles. Secured in the compartment beneath the overlapping flap 23 is a money purse 31, while secured to the inner side of this flap 23 is a mirror 32. Thus, this invention provides a compact having 10 the most important toilet or vanity articles easily accessible yet in separate compartments so that each article may be used without disturbing or exposing the others. When the overlapping flap 23 is closed, it, in conjunction 15 with the other flaps, provides a closure means for the compact, and flap 23 overlaps and protects the fastening means of the other flaps, so that it is necessary to first open flap 23, and then any one or more of 20 the other flaps may then be opened. Accordingly, as the mirror is an essential article in using any vanity article, it is placed on the inside of this overlapping flap, and the money 25 purse is in the compartment beneath this flap, 23 that it may be available without disturbing or exposing any of the other vanity articles, and further, by placing the purse and mirror in the same compartment, the 30 mirror may be consulted or access to the money purse may be had when the flap 23 is opened without exposing any of the other vanity articles.

The compact may be made of leather, imitation leather or any other similar or suitable 35 material. This compact thus provides a convenient means of carrying the five most important articles needed by the average female user. If desired, however, means may be provided for additional articles within the scope 40 of this invention. Thus, the inner sides of the other flaps may be used to secure additional vanity articles. Furthermore, instead of being substantially rectangular as shown, which 45 is the preferred form, thus having four sides, the compact may be a polygon in shape having five, six or more sides with an additional closure flap and compartment for each additional side, which additional flaps may 50 have their apexes secured in a central block, thus providing additional separate compartments for additional vanity articles.

Having thus set forth the nature of this invention, what is claimed is:

1. A pocket book compact comprising a 55 case, a substantially triangular flap hinged to each side of said case, each of said flaps having one element of a fastener at its apex, means in the case to secure the other element of a plurality of fasteners, a plurality of 60 fastener elements on said means and adapted to cooperate with the fastener elements on the respective flaps with the exception of one flap, whereby said flaps may be individually secured closed and individually opened, the 65 excepted flap overlapping the apexes of the

other flaps, an element of a fastener secured on one of the overlapped flaps, and adapted to co-operate with the fastener at the apex of the overlapping flap, and said flaps substantially dividing said case into a plurality of compartments each adapted to receive a 70 toilet article.

2. A pocket book compact consisting of a substantially rectangular back panel, a wall on each side of said back panel, a pair of substantially triangular flaps hinged to the opposite end walls on said panel and having their apexes meeting approximately at the center of the panel, a third substantially triangular flap hinged to the wall at the bottom of the panel and having its apex meeting the said other apexes at the center of the panel, means to fasten said apexes at the center of the panel whereby each flap may be opened independently of the other two, a fourth flap hinged to the wall at the top of the panel having its apex substantially overlapping said other apexes, means on said third flap to fasten the apex of said fourth flap thereto, and means to secure a vanity 80 article on said panel beneath one or more of each of said flaps and on the inside of at least one of said flaps.

3. A pocket book compact consisting of a substantially rectangular back panel, a wall on each side of said back panel, a pair of substantially triangular flaps hinged to the opposite end walls on said panel and having their apexes meeting approximately at the center of the panel, a third substantially triangular flap hinged to the wall at the bottom of the panel and having its apex meeting the said other apexes at the center of the panel, means to fasten said apexes at the center of the panel whereby each flap may be opened independently of the other two, a fourth flap hinged to the wall at the top of the panel having its apex substantially overlapping said other apexes, means on said third flap to fasten the apex of said fourth flap thereto, means to secure a vanity article on said panel beneath one or more of each of said first three flaps, a purse secured to said panel beneath said overlapping flap and a mirror secured to the inside of said overlapping flap.

4. A pocket book compact consisting of a substantially rectangular back panel, a wall on each side of said back panel, a pair of substantially triangular flaps hinged to the opposite end walls on said panel and having their apexes meeting approximately at the center of the panel, a third substantially triangular flap hinged to the wall at the bottom of the panel and having its apex meeting the said other apexes at the center of the panel, means to fasten said apexes at the center of the panel whereby each flap may be opened independently of the other two, a fourth flap hinged to the wall at the top of the panel having its apex substantially overlapping said other

apexes, means on said third flap to fasten the apex of said fourth flap thereto, means to secure a vanity article on said panel beneath one or more of each of said first three flaps, a purse secured to said panel beneath said overlapping flap and a mirror secured to the inside of said overlapping flap, and a carrying strap secured across the back of said panel.

5. A pocket book compact comprising a polygonal back panel, a wall on each side of said back panel, a substantially triangular flap hinged to each wall, all of the flaps except one having their apexes meeting approximately at the center of the panel and means at the 10 center for fastening these apexes whereby each flap may be opened independently of any of the other flaps meeting at the center, the excepted flap being substantially larger than the other flaps whereby its apex may overlap 15 the apexes of the other flaps, and means on 20 one of the overlapped flaps to fasten said excepted flap thereto.

In testimony whereof I affix my signature.
RAYMOND KATRINAK.
